UNITED STATES PATENT OFFICE.

NELSON H. BRAY, OF BERKELEY, CALIFORNIA.

ADJUSTER FOR SASHES, DOORS, AND THE LIKE.

Application filed January 23, 1922. Serial No. 531,047.

To all whom it may concern:

Be it known that I, NELSON H. BRAY, a citizen of the United States, and a resident of the city of Berkeley, county of 5 Alameda, State of California, have made a new and useful invention—to wit, Improvements in Adjusters for Sashes, Doors, and the like; and I do hereby declare the following to be a full, clear, concise, and 10 exact description of the same.

The invention relates particularly to a sash adjuster of the friction type.

Among the objects of the invention are to provide means for locking movable objects such as sashes, doors and the like hinged or pivoted to a movable object in the desired adjustment against displacement by wind pressure or otherwise by frictional resistance, sufficient for the purpose 20 but adapted to be overcome by manual operation of the apparatus connecting the movable to the immovable objects. Other objects and advantages will appear as this description progresses.

25 In this specification and the annexed drawing, the invention is illustrated in the form considered to be the best but it is to be understood that the invention is not limited to such form because it may be 30 embodied in other forms, and it is also to be understood that in and by the claims following the description it is desired to cover the invention in whatever form it may be embodied.

35 In the accompanying one sheet of drawings.

Fig. 1 is a view diagrammatically illustrating the application of the adjuster arm to a window sash and casing.

40 Fig. 2 is a vertical cross section through Figure 1 on the line 2—2.

Fig. 3 is a lateral cross section through Fig. 1 on the line 3—3.

Fig. 4 is an end view of the adjuster.

45 Fig. 5 is a perspective view of the adjuster.

Fig. 6 is a section taken through Fig. 1 on the line 6—6.

In detail the construction illustrated in 50 the drawings includes a bracket 1 provided with a passage 2 therethrough, said bracket having a foot-piece 3, with screw holes 4 therethrough, pivotally or rigidly secured to the said bracket. The foot-piece 3 of 55 the bracket 1 is adapted to be secured to

a relatively immovable object, such, for instance, as a lintel, jamb or other part of a door or window casing.

A somewhat modified form or frictional bracket comprising a casing 6, having 60 screw holes 7 through the base thereof, is adapted to be secured to a relatively movable object, such, for instance, as a sash, door or the like. A pair of spaced finger grips or arms 8 and 9 are adapted to be 65 secured within and to the base of the casing 6 and the opposite ends of said arms, to project through openings provided in the upper face of the said casing 6.

A pair of shafts or arms 11 and 12 of 70 unequal lengths and pivoted together at 13 are adapted to be arranged between and connecting the respective brackets 1 and 6, the shorter shaft 12 being slidably retained in the passage 2 in the bracket 1 and the 75 longer shaft 11 being slidably retained in a transverse opening 14 provided in the casing 6. The opening 14 in the casing 6 is in substantial alignment with elongated holes 15 provided in the pivoted arms 8 80 and 9, whereby when said arms are placed in substantially a parallel position relative to each other, the shaft 11 may be moved freely through the opening 14 in the frame 6 and openings 15 in the arms 8 and 85 9. The shaft 11 is maintained relatively immovable and frictionally retained within casing 6 by placing the arms 8 and 9 out of parallel, whereby the end of slots 15 will engage the shaft 11 and thus create a 90 friction at the points of contact. A spring 95 16 is interposed between the arms 8 and 9 and around the shaft 11 to normally maintain the said arms 8 and 9 out of parallel and to thus frictionally engage the shaft 11.

The shaft 12 is held within the passage provided in the bracket 1 by a set screw 5 whereby the position of the said shaft 12 relative to the bracket may be adjusted or changed at will. A set screw is used in the 100 bracket 1 to contact with the shaft 12 as under ordinary operating conditions the shaft 12 will not be moved after it has been properly located. For instance, the foot-piece 3 of the bracket 1 would be secured to a lintel, jamb or other part 20 of a window or door casing, whereby the pivotal point 13 of the shafts 11 and 12 would lie opposite the joint or hinge point of the sash or door 22 secured to the said jambs or 110

casing 20. The frictional adjuster casing 6 would be located on the rails of the sash or door at a predetermined point where it would readily engage the shaft 11. Should 5 by any chance, the pivotal axis of the connected shafts 11 and 12 become disarranged relative to the hinge point of the sash and casing, the proper relocation may be made by unloosening the set screw 5, releasing the 10 frictional grip exerted in the casing 6 and moving the short shaft 12 to the desired position and then fixing it permanently in position by tightening on the set screw 5.

The brackets 1 and 6 are specifically 15 designated for identification only and may be varied to suit the nature of their application.

In the present instance the bracket 1 is 20 screwed to the lintel, jamb or other part 20, (see Fig. 1) of the window or door casing, by screws passing through the holes 4. The bracket 6 is similarly attached by screwing 25 through the holes 7 engaging the side rail 21 or other part or the sash or door 22. The adjuster is attached to give the desired 30 opening and closing to the sash or door 22, which is conventionally pivoted or hinged in the frame 20. The friction exerted between the moving arm and adjuster bracket 6 frictionally holds the movable sash or door 22 in any position at which it 35 may be placed by the operator. Movement of the sash 22 acting against the friction adjuster 6 is impossible for the cooperating

action of the adjuster 6 and arm 11 exerts 35 sufficient friction to hold the sash in fixed position against ordinary wind or other pressure or resistance.

While this invention has been specifically described in its fabrication as a sash or 40 door adjuster, I do not wish to be understood as limiting it thereto, as it is obviously adaptable for attachment to the various forms of lids of trunks, chests and the like, or wherever a frictional adjuster is 45 applicable.

Having thus described my invention, what I claim and desire to secure by Letters Patent is:

1. A frictional adjuster including a pair 50 of pivotally connected arms; adjustable frictional means for engaging an end of one of said arms and a relatively immovable frictional means for engaging the other arm.

2. A frictional adjuster including a pair 55 of pivotally connected arms and adjustable friction means adapted to be slidably secured to one of said arms and frictional means adapted to be arranged in a relatively 60 stationary position on said other arm.

In testimony whereof, I have hereunto set my hand at San Francisco, California, this 31st day of December, 1921.

NELSON H. BRAY.

In presence of—
LINCOLN V. JOHNSON.
